RURAL MAIL BOX SIGNAL

Roy William Reed, Mission, Tex.

Application March 14, 1936, Serial No. 68,944

4 Claims. (Cl. 232—35)

The present invention relates to a signal for use on rural mail boxes to indicate when the same contains mail both as far as the owner is concerned and the mail carrier.

5 The object of the invention resides in the provision of a signaling device which will fall to an inoperative position upon opening of the door of the rural mail box.

Another important object of the invention resides in the provision of a signal of this nature which is exceedingly simple in its construction, inexpensive to manufacture and install, thoroughly efficient and reliable in use and operation and otherwise well adapted to the purpose for 10 which it is designed.

15 With the above and numerous other objects in view as will appear as the description proceeds, the invention consists in certain novel features of construction, and in the combination and arrangement of parts as will be hereinafter more fully described and claimed.

In the drawings:—

Figure 1 is a side elevation of a rural mail box showing my signal mounted thereon in signaling position.

20 Figure 2 is an end elevation thereof.

Figure 3 is a detail sectional view taken substantially on the line 3—3 of Figure 1.

Figure 4 is a fragmentary elevation of the box showing the signal in its non-indicating position.

30 Referring to the drawings in detail, it will be seen that the numeral 5 denotes a conventional rural mail box with the usual hinged door 6 associated therewith. The plate 7 is secured by suitable means 8 to the door 6 and has a lug or pin 9 projecting therefrom laterally outwardly beyond one side of the door. On said side of the box 5 there is mounted a bolt 10 on which is 35 rockably supported a flat arm 11 an intermediate portion of which is offset inwardly to provide a bearing shoulder 12 which is rockable on the bolt. Except for the bearing shoulder 12 the arm 11 is spaced from the side of the box to overcome wiping engagement with the box and eliminate 40 the possibility of the arm freezing fast to the box in winter weather. The rear end of the arm has an outwardly projecting lip 14. On one side in close proximity to the forward end, the arm is provided with a notch 15 the outermost edge 16 45 of which is in the form of an arcuate cam for cooperating with the pin 9 so that when the door is swung to an open position the arm will be rocked. Notch 15 extends from the lower side of the arm 11 and cam edge 16 curves upwardly and inwardly. A staff 18 is bolted as at 19 to the end

5 of the arm adjacent the lip 14, the lip 14 preventing the rocking of the staff. On the upper end of this staff is a flag plate or signal 20. A hook bracket 21 is fixed as at 22 to the side of the box 5. When the door 6 is swung to an open position the pin 19 engages the cam surface 16 in the notch 15 thereby swinging the arm 11 and causing the signal flag to move from the position shown in Figure 1 to the position shown in Figure 4 and in the latter position the staff 18 is 10 supported in the hook bracket.

15 It is thought that the construction, utility, manipulation and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the 20 invention and the above description.

25 It will be apparent that changes in the details of construction, and in the combination and arrangement of parts may be resorted to without departing from the spirit or scope of the invention as hereinafter claimed or sacrificing any of its advantages.

What is claimed is:—

1. In combination with a rural mail box equipped with a hinged lid, a pin on the lid extending laterally from one side thereof, an elongated flat actuating arm formed with a notch in the lower side thereof in close proximity to one end to receive the pin when the lid is closed, the outermost edge of said notch being arcuate 30 to provide a cam to rock the actuating arm when the lid is opened, an intermediate portion of said arm having an offset portion to provide a relatively small bearing shoulder, said shoulder portion pivoted to the box thereby spacing the parts 35 of the arm on each side thereof to prevent wiping contact with the box, a signal staff, means for securing one end of the staff to the other end of said arm, a signal carried by the free end of said staff, said securing means consisting of a bolt 40 and a lip on the end of the arm engaging in overhanging abutment a side portion of the staff, and a hook bracket carried by the box for supporting the staff when in a lowered position.

2. In combination with a rural mail box 50 equipped with a hinged lid, a pin on the lid extending laterally from one side thereof, an actuating arm formed with a notch in the lower side thereof in close proximity to one end to receive the pin when the lid is closed, the outermost 55

edge of said notch being arcuate to provide a cam to rock the actuating arm when the lid is open, an intermediate portion of said arm having an offset portion to provide a bearing shoulder, said shoulder portion being pivotally secured to the box to space the parts of the arm on each side thereof to prevent wiping contact with the box, a signal staff, means for securing one end of the staff to the other end of the arm, 10 a signal carried by the free end of said staff, and a hook bracket carried by the box for supporting the staff when in a lowered position.

3. A signal for use with mail receptacles having a horizontally pivoted door and a latch therefor, a rod-like horizontal extension secured to and projecting outwardly a predetermined distance from one side edge of the door, an arm pivoted intermediate its ends to the receptacle, and a signalling member secured to one end of 20 the arm and extending at right angles thereto, the opposite end of said arm being formed with a downwardly opening and upwardly and rearwardly extending notch to receive the rod-like extension when the door is moved to and latched 25 in closed position and to retain said signalling member against movement when in its operative

position, said notch having one of its defining walls curved to cooperate with said rod-like extension to move the signal to inoperative position when the door is opened.

4. A signal for use with mail receptacles having a horizontally pivoted door and a latch therefor, a plate member secured to the outer face of the door intermediate the upper and lower edges of the latter, a rod-like horizontal extension formed integral with the plate member and projecting outwardly a predetermined distance from one side edge of the door, an arm pivoted intermediate its ends to the receptacle, and a signalling member secured to one end of the arm and extending at right angles thereto, the opposite end of said arm being formed with a downwardly opening and upwardly and rearwardly extending notch to receive the rod-like extension when the door is moved to and latched in closed position and to retain said signalling member against movement when in its operative position, said notch having one of its defining walls curved to cooperate with said rod-like extension to move the signal to inoperative position when the door is opened.

ROY W. REED.
